UNITED STATES PATENT OFFICE.

WOLFGANG GAEDE, OF FREIBURG, BREISGAU, GERMANY.

ROTARY MERCURY VACUUM-PUMP.

No. 921,585.

Specification of Letters Patent.

Patented May 11, 1909.

Application filed August 27, 1908. Serial No. 450,509.

To all whom it may concern:

Be it known that I, WOLFGANG GAEDE, a subject of the German Emperor, residing at Salzstrasse 13, Freiburg, Breisgau, Germany, 5 have invented certain new and useful Improvements in Rotary Mercury Vacuum-Pumps; and I do hereby declare the following to be a full, clear, and exact description of the invention, such as will enable others 10 skilled in the art to which it appertains to make and use the same.

This invention relates to a safety device for the bucket wheels of mercury vacuum pumps, the object of the device being to prevent 15 damage of the bucket wheels when air is inadvertently allowed to enter the pump rapidly or when the receiver suddenly breaks.

It has been found that the splitting of the bucket drum always occurs when the drum is 20 in such a position that one of the highly evacuated spaces or channels in it is cut off on all sides by mercury from the connection with the receiver and the rest of the pump. If, while the drum is in this position air enters 25 the pump quickly, the empty space in question is so rapidly filled with mercury, that the latter strikes on the wall of the drum violently and breaks the wall.

The invention consists in providing the 30 walls which are liable to receive such shocks with elastic seals, such as openings closed by elastic membranes, or spring valves. When the mercury rushes into the empty space its motion is not stopped at the moment when it 35 fills the space but is able to continue by virtue of the elasticity of the seal. It has been found that drums provided with such seals survive even quite sudden inrushes of air like that caused by breakage of a receiver, 40 without any damage, even though the drum be made of brittle material, such as porcelain.

In the accompanying drawings, the Figures 1, 2 and 3 are diagrammatic sections through such a drum at right angles to its 45 axis, the drum being placed in the dangerous position.

The drum is shown of the same construction and in the same position in all the figures but the invention is independent of the construction of the drum and can be used for any part of the drum where a hollow space is cut off only by mercury from entering air.

Fig. 1 represents the mercury rising in the space cut off by the mercury bath, that is to

say in this case the channel z , under the pressure of the entering air. The two columns are just about to meet at the point A and thereafter to produce the shock on the wall of the drum.

Fig. 2 shows one form of the invention. 60 In the outer periphery of the drum there is a number of perforations v which are all closed by a rubber band w stretched over them. When the mercury has filled the channel z it can continue to move through 65 the openings raising the rubber band slightly in so doing.

Fig. 3 shows a somewhat modified form in which the perforations v are not on the periphery of the drum but on the end surfaces of the drum. The rubber sheet closing these holes is in this case extended over the whole surface of the drum. When a concussion occurs the rubber sheet extends slightly outward although the mercury 75 itself does not escape. As soon as the mercury comes to rest it is pressed back by the elasticity of the rubber.

Fig. 4 shows another construction of the elastic seal which can be used to advantage 80 when the openings v are on the end surface of the drum. The laminar spring F keeps the rubber stopper K in the perforation v , but the pressure of the mercury from within the drum forces the rubber stopper outward and the valve is opened.

Having thus described my invention, I claim:

1. In a mercury vacuum pump, the combination, with the bucket-wheel which rotates in the mercury bath, of an elastic seal in the wall of the bucket.

2. In a mercury vacuum pump, the combination of a bucket-wheel, a body of mercury in which the wheel rotates, and elastic seals in the wall of the bucket at places liable to fracture.

3. In a mercury vacuum pump, the combination of a bucket-wheel having perforations in its wall, and a rubber sheet stretched 100 over the surface of the wall and covering said perforations.

4. In a mercury vacuum pump, the combination of a bucket-wheel having a mercury channel at its outer part into which the mercury passes in two columns which move toward each other, and elastic seals comprising a resilient member extending over the bucket-

wall and covering perforations communicating with said channel.

5. In a mercury vapor pump, the combination of a bucket-wheel, and elastic seals placed in the wall of said wheel where they are submerged when in communication with the vacuum.

In testimony, that I claim the foregoing as my invention, I have signed my name in presence of two subscribing witnesses.

WOLFGANG GAEDE.
